SPOON OR SIMILAR ARTICLE

Karl Peters, Jr., Solingen, Germany

Application September 19, 1955, Serial No. 37,974

Claims priority, application Germany August 2, 1955

Term of patent 14 years

(Cl. D54—12)

FIG. 1

FIG. 2

FIG. 3

FIG. 4

FIG. 6

FIG. 5

Fig. 1 is a left side view of a spoon, showing my new design;

Fig. 2 is a front view;

Fig. 3 is a right side view;

Fig. 4 is a rear view;

Fig. 5 is a fragmentary end elevational view; and

Fig. 6 is a developed plan view of the handle portion thereof, illustrating the ornamental pattern in detail.

The essential features of the design reside in the handle portion shown in full lines on the drawings.

I claim:

The ornamental design for a spoon or similar article, as shown and described.
